CLAIM

The ornamental design for a lanyard for controller as shown and described.

DESCRIPTION

FIG. 1 is a perspective view of front, top and left side of a lanyard for controller showing my new design;

FIG. 2 is a perspective view of rear, top and right side thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged view of portion 9 shown in FIG. 1;

FIG. 10 is an enlarged view of portion 10 shown in FIG. 2;

FIG. 11 is an enlarged view of portion 11 shown in FIG. 3;

FIG. 12 is an enlarged view of portion 12 shown in FIG. 5;

FIG. 13 is an enlarged view of portion 13 shown in FIG. 6;

FIG. 14 is an enlarged view of portion 14 shown in FIG. 7; and,

FIG. 15 is an enlarged view of portion 15 shown in FIG. 8.

The portions of the article in dash-dot broken lines depict portions of the lanyard for controller that form no part of the claimed design.

The dot-dash broken lines encircling an enlargement portion of the design forms no part of the claimed design.
